UNITED STATES PATENT OFFICE.

JULIUS REYNOLDS KLINE, OF CHICAGO, ILLINOIS, ASSIGNOR TO PATRIOTIC ANCIENT AND HONORABLES OF THE GRAND ARMY OF THE REPUBLIC, OF CHICAGO, ILLINOIS, A CORPORATION OF ILLINOIS.

DESIGN FOR A BADGE.

No. 38,765.

Specification for Design.

Patented Aug. 27, 1907.

Application filed February 28, 1907. Serial No. 359,941. Term of patent 7 years.

To all whom it may concern:

Be it known that I, JULIUS REYNOLDS KLINE, a citizen of the United States, residing at Chicago, in the county of Cook and State of Illinois, have invented a new, original, and ornamental Design for Badges, of which the following is a specification, reference being had to the accompanying drawings, forming a part thereof.

The figure is a plan view of a badge, showing my new design.

I claim.

The ornamental design for a badge, as shown.

JULIUS REYNOLDS KLINE.
